United States Patent Office

Des. 186,255
Patented Sept. 29, 1959

186,255

FOOT MASSAGE UNIT

William N. Moxley, Los Angeles, Calif.

Application October 27, 1958, Serial No. 53,160

Term of patent 14 years

(Cl. D83—1)

Fig. 1.

Fig. 2.

Fig. 3.

Figure 1 is a front elevational view of a foot massage unit showing my new design, the rear being substantially plain;

Fig. 2 is a side elevational view thereof;

Fig. 3 is a top plan view thereof.

I claim:

The ornamental design for a foot massage unit, substantially as shown and described.
